UNITED STATES PATENT OFFICE.

ANTHONY W. PERMENTO, OF SAN FRANCISCO, CALIFORNIA.

BRUSH-HANDLE SCRAPER ATTACHMENT.

SPECIFICATION forming part of Letters Patent No. 598,349, dated February 1, 1898.

Application filed July 28, 1897. Serial No. 646,227. (No model.)

To all whom it may concern:

Be it known that I, ANTHONY W. PERMENTO, a citizen of the United States, residing in the city and county of San Francisco, State of California, have invented an Improvement in Brush-Handle Scraper Attachments; and I hereby declare the following to be a full, clear, and exact description of the same.

My invention relates to improvements in scraping attachments for brushes and similar articles.

It consists of the parts and the constructions and combinations of parts hereinafter described and claimed.

15 The accompanying drawings illustrate the construction and operation of my devices.

Figure 1 shows the scraper-blade pivoted to the handle in connection with a spring to return it. Figs. 2, 3, 5, 6, and 7 show the blade 20 operated by two pins in slots *f*. Fig. 4 is a cross-section on line *y y* of Fig. 3.

The object of my invention is to provide attachments for blacking, paint, and other brush handles which may be used as scrapers 25 when desired and when not in use can be concealed within the handle and out of the way.

It will be manifest that various forms of these scrapers may be employed and various means for moving them so as to be projected 30 or concealed.

In Fig. 1 I have shown the blade *A* pivoted in a slot or channel made in the handle *B*. The blade, which may be of any suitable material, has the pivot-pin at the inner end 35 and is of such shape as to normally conform with the shape of the handle not projecting therefrom. By means of a projecting lug or plate *D* the blade can be pressed so as to project from one side, and the blade can then be 40 used for scraping purposes. When released, the blade is returned into the handle by means of a spring *E*.

Figs. 2, 3, 4, 5, 6, and 7 show the blade *A'* having slots made in it, and pins passing

through the handle and through the slots in 45 the blade normally retain the blade in place. The blade, sliding in the channel, as before described, may be retracted, the slots sliding upon the pins *C*, so that the blade lies flush within the handle. When it is to be protruded, it is caused to slide upon the pins and is locked in place by the angular turns in the openings in such a manner that the blade 50 will not be forced back when in operation. In order to retract it, it is only necessary to 55 push it until the straight portion of the slot is in line with the direction in which it is desired to move the blade. The latter may then be pushed back into place, being either retained by the friction of the parts or locked 60 by the formation of the slots which are slideable upon the fixed pin or pins.

Having thus described my invention, what I claim as new, and desire to secure by Letters Patent, is—

1. A handle having a slot or channel in the end, and a blade slideable longitudinally and also substantially transversely therein whereby the edge of the blade may be protruded beyond the plane of the end and side of the 70 handle, and retracted and concealed within said handle.

2. A handle with a slot or channel made in the end, a blade slideable in the channel and conforming substantially in outline to the 75 shape of the handle, substantially cam-shaped slots in said blades and pins in the handles engaging said slots whereby the blade may be moved longitudinally and substantially transversely to project its end beyond the end of 80 the handle and its edge beyond the side thereof.

In witness whereof I have hereunto set my hand.

ANTHONY W. PERMENTO.
